IRON HOLDER FOR ATTACHMENT TO
IRONING BOARDS

John E. Mallett, Miami, Fla.

Application July 19, 1948, Serial No. 39,506

5 Claims. (Cl. 248—117.4)

1

The present invention relates to supporting and holding means for flat irons and especially electrically heated sadirons and has more particular reference to a device which takes the form of a rack and which is clamped or otherwise mounted on the rear leg-supported end of a portable or equivalent ironing board whereby when the iron is not in use it may be quickly shifted to a convenient out-of-the-way safely supported position.

As the introductory statement of the invention implies, I am conversant with the general state of the art to which the present invention relates and realize that there are various forms and styles of sadiron supporting and holding racks. It follows, therefore, that the principal object of the present invention is to structurally, functionally and otherwise improve upon racks of the form stated and to provide a novel rack which is possessed, by contrast with prior art devices, of appreciable refinements and improvements.

One object of the invention is to provide a sadiron supporting and holding rack which lends itself to ready and practical manufacture from metal or equivalent stock, which is open work for free ventilation of the iron and which, while it may be constructed from perforated sheet material, is preferably and more satisfactorily constructed from wire of proper gauge and strength.

An outstanding object of the invention is to provide an open work sadiron accommodating and holding rack which is attachable to one end of the ironing board in a manner to project beyond said end, the construction being such that the rack is yieldably resilient so that when the weight of the iron is brought to bear thereon, said rack tilts or slants rearwardly and downwardly in a manner to adequately hold the sadiron clear of direct contact with the usual covering material on the ironing board.

Another feature of the invention has to do with a rack of the stated type which is characterized by an upstanding retainer, said retainer being designed to partly embrace the usual heel on the sadiron, whereby to virtually "lock" the sadiron on the rack and to thereby minimize the likelihood of improper racking of the iron and accidental displacement once it is fitted on the rack.

Another feature has to do with the aforementioned objective wherein the retainer insures proper racking of the iron and also facilitates springing the rack to the stated inclined position in an obvious manner.

A further object of the invention is to provide a readily attachable and detachable sadiron rack having the stated features and advantages and further advantageous in that it does not require the use of screws, bolts or other type special fasteners for purposes of attaching and

2

maintaining the rack on the ironing board. More specifically the invention has to do with an open work wire rack with a retainer for the heel of the iron at the rear end of the rack and with forwardly extending attaching arms, said arms being constructed to intimately coat with the top and bottom surfaces of the board, and the free terminals of the forward ends of the arms being laterally bent toward each other to provide hooks which partly engage the usual supporting legs on the ironing board, whereby to provide reliable and satisfactory ways and means of connecting the rack with the conventional type ironing board.

Other objects, features and advantages of the invention will become more readily apparent from the following description and the accompanying illustrative drawing.

In the drawing, wherein like numerals are employed to designate like parts throughout the views:

Figure 1 is a fragmentary top plan view of the rear leg-supported end portion of a conventional portable or folding ironing board showing my improved sadiron holding and supporting rack and the manner in which it is constructed and attached;

Figure 2 is an edge or side elevational view of the structure seen in Figure 1;

Figure 3 is a view like Figure 2 showing, in dotted lines, the sadiron seated on the rack and the manner in which the rack yields and tilts in relation to the ironing board;

Figure 4 is a section on the line 4—4 of Figure 3, looking in the direction of the arrows.

Referring now to the drawing by distinguishing reference numerals and lead lines, the numeral 6 denotes a conventional portable or folding type ironing board having supporting legs 7 at its rear end 8.

The rack for the sadiron 9 is denoted, in a general way, by the numeral 10. Said rack is of any suitable reticulated or open work form but is preferably constructed from wire and of the specific style and form represented in the drawing. The rack proper may be alternatively referred to as a frame, the same being of a general U-shaped form and including spaced parallel limbs 11 and a laterally bent bight portion 12. This bight portion provides an upstanding loop-like retainer which partly embraces the heel 13 of the iron 9 as shown in Figure 3. The rack is completed by the provision of transverse parallel spaced cross rods or wires 14 arranged, as shown and welded or otherwise secured in place.

To assist in describing the construction, the extensions forming forward portions of the limbs are referred to as attaching and sustaining arms. These arms are of duplicate construction. The rear end portions 15 of the arms connect with

the limbs 11 by way of U-bends 16 which serve as stops and which engage the rear edge portion of the ironing board in the manner shown.

These bends are primarily springs and provide the desired resilient and elastic properties desired. Links 17 are attached to and embrace the bends to prevent the same from spreading and permitting the rack to become too flexible. The stated rear end portions 15 of the arms are slightly curvate and are somewhat diagonal to the corner portions of the board which they overlie. The intermediate portions 18 of the arms are directed downwardly and forwardly and lie alongside of the edge portion of the ironing board, as shown in the drawing. The forward ends of said intermediate portions are then laterally bent inwardly and toward each other as at 19 to provide what may be referred to as attaching hooks. The hooks underlie the ironing board and rest against and satisfactorily contact the forward faces of the legs 1. It will be seen therefore that by simply spreading the arms apart, the hooks may be slipped beneath the board and connected to the legs whereby to properly apply the arms, to attach same to the ironing board and to position the rack in the wanted position, that is projecting rearwardly beyond the rear end of the ironing board. In actual use, the rack is of sufficient area to accommodate the present day sadirons. Moreover, since most common types of irons are provided with projecting heel portions, the retainer 12 will serve to embrace the heel portion and thus facilitate proper heating and retention of the sadiron.

The resiliency of the wire is such that the attaching arms may be readily spread apart for convenient attachment purposes. When the arms are released they automatically spring together and are self retained to satisfactorily hold the rack on the ironing board. Rack portion 10 is substantially rigid as a unit but is connected with the resilient arms by way of the U-shaped springs or bends 16. Thus, the bends serve not only as stops to coact with the hooks insatisfactorily applying and retaining the arms but function to give added yieldable and resilient properties to the rack. It follows that when the rack is not in use it is in a substantially horizontal plane approximately even with the top of the board. Then, when the sadiron is not in use it is simply slid rearwardly and glides or rides over the arm bends or rear end portions 15 and these serve to track and guide the iron onto the rack. When the iron is situated as shown in Figure 3 with the heel 13 in the loop retainer 12, the weight of the iron puts the rack under tension and hence the rack inclines rearwardly and downwardly. Thus, the iron is lodged in the retainer 12 and by being in this inclined state is not likely to be accidentally knocked off or otherwise displaced. However, it is in readiness to be readily picked up and brought back into use in an obvious manner. It is further clear that the rack thus tilted holds the iron clear of the ironing board and overcomes the likelihood of burning the covering of the ironing board or garment in position on the ironing board.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. An attachment for a conventional-type ironing board having depending supporting legs comprising a sadiron holding rack, said rack having outstanding attaching limbs with laterally bent free end portions, the latter being releasably connectible with said legs.
2. An attachment for a conventional-type ironing board having depending supporting legs comprising a sadiron holding rack, said rack having outstanding attaching limbs with laterally bent free end portions, the latter being releasably connected with said legs, portions of said limbs lying atop said ironing board and serving to track and guide the sadiron from the board onto said rack.
3. An attachment for a conventional-type ironing board having vertical supporting legs comprising a sadiron supporting and holding rack, said rack having forwardly extending arms, the forward free terminals of said arms having in-turned hooks underlying the board and releasably connected with said legs, the intermediate portions of said arms lying alongside of the adjacent edge portions of the board and the rear end portions of the arms resting upon the top of the board.
4. An ironing board sadiron holding attachment of the class described comprising a substantially flat rectangular openwork frame constituting a rack, the latter being of a width considerably less than the width of said board, and forwardly projecting arms carried by said frame, said arms being adapted to releasably mount the frame on the rear end portion of a leg-supported ironing board, the free terminal end portions of said arms being laterally bent to provide leg engaging hooks, the intermediate portion of said arms being substantially straight from end to end and parallel with each other and the rear end portions being disposed in rearwardly diverging relation whereby to permit said rear end portions to rest atop the board, the forward ends to engage beneath the board and the intermediate portions to reside alongside the edges of the board.
5. An attachment for an ironing board comprising a substantially flat rectangular wire frame of general U-shaped form including opposed limbs wires connecting said limbs, the bight portion of said frame being laterally bent to provide a retaining loop for the heel portion of an iron, and means for attaching the frame to an ironing board, said means embodying hook equipped attaching arms connectable with portions of the ironing board, said arms being connected with the limbs of said frame by U-bends, said U-bends being reinforced by stabilizing links and being lateral to the plane of the frame to function as stop members.
